UNITED STATES PATENT OFFICE.

ALBERT J. HANSON, OF ARLINGTON, MASSACHUSETTS, ASSIGNOR TO AMERICAN METALLURGICAL CORPORATION, OF BOSTON, MASSACHUSETTS, A CORPORATION OF MASSACHUSETTS.

ELECTRIC RESISTANCE FURNACE.

Application filed January 23, 1924, Serial No. 687,913. Renewed May 7, 1927.

This invention relates to an electric resistance furnace.

One object of the invention is to provide an electric resistance furnace of novel and improved construction, particularly with respect to the supporting of the resistor within the furnace, to produce a furnace which is simple, durable and capable of maximum efficiency in operation, and also one in which the liability of short-circuiting the resistor and burning out the same are reduced to a minimum.

Another object of the invention is to provide a furnace of the character specified which may be constructed in a simple and inexpensive manner, and particularly one in which the resistor sections may be installed and removed at a minimum expense and in a simple and convenient manner.

A still further object of the invention is to provide a novel and improved construction of resistor support for electric resistance furnaces.

To these ends, the resistor of the electric resistance furnace comprises preferably the usual ribbon bent into a general sinuous shape, having a plurality of bends at opposite sides thereof, and the resistor support comprises a body of electrical insulating material, preferably having high thermal transmitting and radiating properties, and which is preferably embedded in and arranged to project from a wall of the heating chamber of the furnace to support the resistor thereon.

In the preferred embodiment of the invention, the resistor support comprises a pre-formed tile adapted to be laid up between the brick in a wall of the heating chamber of the furnace and to project from the wall to form, in effect, a supporting shelf. Each resistor section is preferably arranged to be supported upon and to rest directly upon the projecting portion of the resistor support, and the latter preferably has provision for maintaining the bends of the resistor in spaced relation to one another and in spaced relation to the wall of the heating chamber. By supporting the resistors by resting their lower

bends by gravity on their supports, there is no opportunity for the weight of a resistor when at high temperature to cause its attenuation with consequent decrease of effective cross section with its resultant danger of overheating and burning out, a condition which it is found in practice is liable to occur when the resistor is suspended at its upper bends, the weight of the resistor then subjecting it to tension stresses which in its softened condition at high temperature it is not able to withstand. The projecting portion of one resistor support is preferably arranged to cooperate with the upper bends of a resistor section arranged beneath the same and retain the upper end of such lower resistor section in operative position, with the upper bends maintained in spaced relation. Provision is also preferably made for removably retaining the lower bends of each resistor section in their proper positions upon the resistor support, as will be described. The resistor support may, and preferably will, comprise a unitary structure adapted to be laid up between the brick of the furnace wall in a manner such that a plurality of the resistor supports cooperate to form a projecting shelf for supporting the resistor sections.

These and other features will be herein-after described, and particularly pointed out in the claims at the end of the specification.

In the drawings illustrating the preferred embodiment of the invention,

Figure 1 is a perspective of the improved resistor support.

Figure 2 is a section on line 2-2 of Figure 1.

Figure 3 is a perspective of one of the devices for retaining the resistor upon the resistor support.

Figure 4 is a vertical section of a portion of the wall of the heating chamber, illustrating the resistors and their manner of support.

Figure 5 is a front view of a portion of the face of the wall illustrated in Figure 4; and

Figure 6 is a perspective of one of the auxiliary supports to be referred to.

Referring to the drawing, 10 represents a portion of one wall of the heating chamber of an electric resistance furnace, which may be of the usual construction, and 12 a resistor 5 of any usual or preferred construction. Preferably as illustrated in Figure 5, it comprises the usual nickel chromium ribbon of a general sinuous shape having a plurality of bends 13, 14 at the opposite sides thereof. 10 The resistor 12 is preferably built in sections, which are installed in the furnace and electrically connected in any well known manner. In accordance with the present invention, the sections of the resistor 12 are supported 15 upon the wall 10 of the heating chamber of the furnace by preformed insulating supporting members 15 embedded in the wall and having portions 16 projecting from the face of the wall and upon which the resistor sections are supported. As herein shown, the resistor supports which comprise preformed tiles of electrical insulating material, such as carborundum, crystolon, or similar material having high electrical insulating properties 20 at high temperatures, and, in addition, good thermal transmitting and radiating properties, are laid up between adjacent brick in the construction of the wall of the heating chamber, as illustrated in Figure 4. 25 Provision is made for removably mounting the resistor sections in operative substantially upright position upon the projecting portions 16 in a novel manner to permit the sections to be installed and removed in a simple and 30 convenient manner, and for this purpose as herein shown, the resistor supports 15 are arranged to project from the face of the wall to form a series of transversely extending shelves arranged one above the other and spaced from one another slightly more than 35 the height of the resistor section 12 which it is desired to employ. A resistor section is arranged to rest upon the upper surfaces of the resistor supports 15 forming each shelf, and the under portions of the resistor supports of the next higher shelf are constructed 40 to cooperate with the upper ends of the resistor section to retain it in operative position while supported on the next lower shelf. 45 Provision is also made for spacing the individual bends 13, 14 or parts of each resistor section from one another, and also from the wall of the furnace, and as illustrated in the drawing, both the upper and lower surfaces 50 of the projecting portions 16 of the resistor supports 15 are provided with grooves 25, 26 of a size sufficient to receive the upper and lower bends 13, 14 of the resistor. The grooves 25 and 26 are spaced 55 apart in staggered or offset relation to provide intervening bodies 28, 29 of insulating material, and the walls of the grooves also serve to restrain the sections from transverse movement. The forward ends of the grooves 60 65 25 in the under surface of the resistor sup-

ports are closed by retaining members 30 preferably comprising a part of the front wall 31 of each support, as illustrated in Figure 1, and which cooperate with the upper bends 13 of the resistor to prevent forward displacement thereof. By reference to Figures 4 and 5, it will be seen that each resistor section is supported upon a resistor support with the lower bends 14 thereof resting in the grooves 26 in the upper surface of the resistor support, and that each section is retained at its upper end with the upper bends 13 loosely received in the grooves 25 in the under surface of the next higher resistor support, by the members 30 closing the forward ends of the grooves. In order to prevent displacement of the lower bends 14 of each resistor section, a series of lips 34 are preferably provided at the forward ends of the insulating portions 29 between the grooves 26 in the upper surface of the resistor support, as illustrated in Figures 1 and 2, and one or more transversely extending retaining members 36, preferably of lava, or other refractory material having electrical insulating properties and preferably good thermal transmitting and radiating properties, rests upon the upper surface of the resistor support immediately in front of the resistor section and between it and the lips 34. The retaining members 36 are held in place by gravity, and are prevented from forward displacement by the lips 34.

In order to insulate the resistor sections from the face of the wall of the heating chamber, the resistor supports 15 are preferably laid up in the wall in a manner such as to cause the rear ends 38 of the grooves 25, 26, and consequently the rear of each resistor section, to be spaced a short distance from the face of the wall, as illustrated in Figure 4.

In practice, the resistor supports 15 are, as has been stated, composed of carborundum or other similar material, having high electrical insulating properties at high temperatures, and good thermal transmitting and radiating properties, and the resistor supports are preferably cast in the form illustrated in Figure 1, having the grooves 25, 26 in the upper and lower surfaces thereof offset to permit the resistor supports to be laid up one above the other and to have the grooves 25, 26 in the correct position to receive the upper and lower bends 13, 14 of the usual sinuous shaped resistor, such as is illustrated in Figure 5. This construction of resistor supporting member 15 possesses strength, and there is therefore little liability of its fracture during the normal use of the furnace.

In the construction of the electric resistance furnace, the precast resistor-supporting members 15 are shipped to the job and laid up between the fire brick comprising the face of the wall of the heating chamber to form an

- integral part of the wall. In practice, the resistor supports are preferably cast substantially one inch in thickness, so that using the usual two inch brick, the mason by laying up 5 the resistor supports with a double course of the two inch brick intervening, provides a distance between the resistor supports of substantially five inches, this being slightly greater than the height of the resistor section commonly employed. In order to install the resistor sections, the workman bends the resistor ribbon into the desired shape, preferably the sinuous shape illustrated in Figure 5, and thereafter inserts the upper 10 bends 13 of each section in the grooves 26 on the under side of the upper resistor support. It is possible to do this by inclining the resistor section and slipping the upper bends beneath the members 30, closing the forward 15 ends of the grooves 25. When the upper bends 13 of the resistor section have been thus placed in the grooves 25, the lower bends 14 are slid into the grooves 26 upon the upper surface of the lower resistor support, the 20 grooves 26 being open at their forward ends readily permitting this to be done. Thereafter the operator simply drops the retaining members 36 in position in front of the resistor section, the members being retained by 25 gravity in their operative position and prevented from forward displacement by the retaining lips 34 projecting from the surface of the resistor support. It will therefore be apparent that the resistor sections may be installed in an exceeding simple and practical 30 manner, in a minimum of time, and at a relatively small expense. In a similar manner, they may be easily and conveniently removed, all that is required being for the operator to 35 remove the retaining members 36, to slide out the lower ends of the resistor sections, and then drop the sections down until the upper 40 bends 13 clear the members 30 which close the front of the grooves 26.
- 45 In order to insure against the possibility of sagging of the upstanding loops of the resistor sections when the furnace is operated at high temperatures, auxiliary supporting members 40 may and preferably will be interposed within each loop of the resistor sections resting upon the portions 29 between the grooves 25 upon the upper surface of the resistor support. The auxiliary supporting members 40 comprise preformed members of 50 insulating material, preferably carborundum or similar material having high electrical insulating properties and good thermal transmitting and radiating properties, and are preferably of a tapered shape, as illustrated 55 in Figure 6. The members 40 are removably retained in an operative position by the upstanding lip 34 and by the members 30 closing the forward ends of the grooves 26 on the lower surfaces of each resistor support, 60 as illustrated in Figure 4. While during the 65 normal operation of the furnace, the auxiliary supports may not be necessary, it is desirable to utilize them when the furnace is to be operated at high temperatures.
- 70 By reference to Figure 4, it will be seen that the resistor supports project forwardly from the wall of the heating chamber beyond the resistor sections, and the projecting portions together with the upstanding lips 34 serve to protect the resistor sections 75 against mechanical damage or breakage from impact with anything which may tip over within the furnace. It will also be observed that the upper and lower bends 13, 14 of each section of the resistor are spaced 80 from each other by bodies 28, 29 of electrical insulating material, and furthermore in the preferred construction of resistor support, the lower bends 14 of one section of the resistor are separated from the upper 85 bends 13 of the next lower resistor section by an intervening body of electrical insulating material comprising the body portion of the resistor support itself, and as a result, the liability of short-circuiting of 90 the resistors is reduced to a minimum.
- 95 The present construction of electric resistance furnace is designed to reduce to a minimum, the liability of burning out the resistors. The manner of supporting the resistors, it will be observed, is such as to expose them for direct radiation into the heating chamber of the furnace, so that when the furnace is operated at high temperature the heat is radiated directly into 100 the heating chamber where it is utilized and the accumulation of heat and the building up of excessive temperatures in the immediate vicinity of the resistor is avoided. This construction therefore is conducive to the 105 long life of the resistors.
- 110 It is also to be observed that in the present construction of furnace, the resistor sections are supported in a manner such that a maximum amount of wall space may 115 be utilized for the resistors, producing a furnace having a maximum electrical capacity per square foot of wall space.
- 120 The term "sinuous" as used throughout the specification and claims, is to be understood as including shapes of resistors having closed bends of various shapes at the opposite sides thereof.
- 125 While the preferred embodiment of the invention has been illustrated and described, it is to be understood that the different features of the invention may be embodied in other forms within the scope of the following claims.
- I claim:
1. In an electric resistance furnace, in combination, a chamber wall, a resistor section having a plurality of bends at two of the opposite sides thereof, insulating members projecting from the wall on opposite

sides of the resistor section and having spaced apart recesses in adjacent surfaces, and means cooperating with said bends for retaining them in the recesses and the resistor section in place upon the chamber wall.

2. In an electric resistance furnace, in combination, a chamber wall, a resistor section having a plurality of bends at two of the opposite sides thereof, insulating members projecting from the wall on opposite sides of the resistor section and having spaced apart recesses in adjacent surfaces, and means for removably retaining the bends of the resistor section in said recesses and the section in place upon the chamber wall.

3. In an electric resistance furnace, in combination, a chamber wall, a resistor section having a plurality of bends upon two of the opposite sides thereof, insulating members projecting from the wall on opposite sides of the resistor section and having recesses in adjacent surfaces, and means co-operating with said bends to retain the section in operative position between said insulating members and having provision for permitting one side of the section to be moved forwardly upon the insulating member to remove the section from between said insulating members.

4. In an electric resistance furnace, in combination, a chamber wall, two insulating members spaced apart and projecting from the wall, a resistor section having bends at two of its opposite sides arranged between said insulating members, and means for retaining the resistor section between said insulating members including recesses in the adjacent surfaces of the insulating members in which the bends are received, means carried by one of the insulating members for preventing forward displacement of one set of bends from one set of recesses, and removable means for preventing displacement of the second set of bends from the second set of recesses.

5. In an electric resistance furnace, in combination, a chamber wall, two insulating members spaced apart and projecting from the wall, a resistor section having a plurality of bends at two of its opposite sides, and means for retaining the resistor section in operative position between the insulating members including grooves in the adjacent surfaces of the insulating members in which said bends are received, one set of grooves being closed at their forward ends and the second set being open, and removable means for retaining the bends in the open grooves.

6. In an electric resistance furnace, in combination, a chamber wall, a resistor section of general sinuous shape having upper and lower bends, and means for removably supporting the resistor section upon the wall in-

cluding insulating members projecting from the wall above and below said section, relating pockets in the under surface of the upper insulating member in which said upper bends are received and prevented from displacement by the walls, recesses in the upper surface of the lower insulating member open at their forward ends and pockets in which said lower bends of the resistor section are received, and retaining means cooperating with the forward lower portion of the resistor sections for preventing forward displacement of the lower bends from said recesses.

7. A resistor support for electric resistance furnaces, comprising a body of electrical insulating material having relatively high thermal transmitting and radiating properties, and provided upon opposite surfaces with grooves spaced apart and offset with relation to one another for the purpose specified.

8. A resistor support for electric resistance furnaces, comprising a tile of electrical insulating material provided upon its under surface with a plurality of grooves spaced apart and closed at one end, and having upon its upper surface a plurality of grooves open at one end.

9. A resistor support for electric resistance furnaces, comprising a tile of electrical insulating material provided with grooves on opposite surfaces thereof spaced apart and with the grooves upon one surface arranged intermediate adjacent grooves upon the other surface, and provided with members projecting above one surface of the tile, for the purpose specified.

10. In an electric resistance furnace, in combination, a chamber wall, resistors each having a plurality of upper and lower bends, and a resistor support of insulating material embedded in the wall and having a portion projecting therefrom provided with depressions in its upper surface in which the lower bends of the resistor rest and depressions in its lower surface to receive the upper bends of the resistors below, said depressions being spaced apart to provide intervening bodies of insulating material between said bends.

11. In an electric resistance furnace, in combination, a chamber wall, resistors each having a plurality of upper and lower bends, and a resistor support of insulating material embedded in the wall and having a portion projecting therefrom provided with depressions in its upper surface in which the lower bends of the resistor rest and depressions in its lower surface to receive the upper bends of the resistors below, said depressions being spaced apart to provide intervening bodies of insulating material between said bends, and said depressions in the upper and lower surfaces being staggered relative to each other.

12. A resistor support having grooves to receive and support the lower bends of a sinuous resistor, and lips projecting upwardly be-

tween said grooves to hold in position a resistor retaining element.

13. In combination, a furnace having a resistor support projecting from a wall thereof, said support having grooves extending inwardly from its edge on its upper face, a sinusous resistor having lower bends resting in said grooves, said support having lips projecting

upwardly between said grooves along its outer edge, and a bar extending along said edge back of said lips and engaging the forward edge of said resistor to retain said bends in said grooves.

In testimony whereof I have affixed my signature.

ALBERT J. HANSON.
